UNITED STATES PATENT OFFICE.

FRANK J. KINZINGER, OF WINDSOR, ONTARIO, CANADA.

MULTIPLE BRICK MOLD.

1,406,460.

Specification of Letters Patent. Patented Feb. 14, 1922.

Application filed March 10, 1921. Serial No. 451,411.

To all whom it may concern:

Be it known that I, FRANK J. KINZINGER, a citizen of the United States, residing in the city of Windsor, Province of Ontario, 5 Dominion of Canada, have invented certain new and useful Improvements in Multiple Brick Molds; and I do hereby declare the following to be a full, clear, and exact description of the invention, such as will enable others skilled in the art to which it 10 appertains to make and use the same.

The invention relates to certain new and useful improvements in multiple molds for poured concrete or cement bricks, blocks 15 and the like, and has for its object to provide a device of the character indicated involving unit mold forming members, each including a base plate adapted to be supported on one longitudinal edge and having applied thereto 20 to a series of right angled plates disposed in contiguous alignment on said base plate, with one leg overlying the base plate and the other leg normal thereto, and end plates to which the several parallel mold forming 25 members are secured, so that the series of legs of the right angle plates on the front face of each base plate engages the rear wall of the adjacent parallel base plate, whereby the majority of the individual mold 30 units are formed by the two types of elements, represented by the base plate and the attached right angle plates, and the multiple mold as a whole is made up of these latter members and the end plates, and may be 35 quickly assembled and knocked down, and may also be extended indefinitely in a longitudinal direction by juxtaposing and connecting assembled multiple units made up of the parts as indicated.

40 The foregoing and other novel features of the invention will be more particularly set forth in the annexed specification, predicated upon the accompanying drawings, in which:—

45 Fig. 1 is a perspective view, broken transversely through the mid section, showing the multiple mold carried by a truck;

Fig. 2 is a broken perspective view of one of the supports which may be used in connection with the mold;

50 Fig. 3 is a broken perspective view of one of the end plates; and

Fig. 4 is a perspective view of one of the unit mold forming members associated with 55 one of the base supports.

Referring to the drawings, 1 indicates the

base plate of one of the multiple mold forming units, which plate 1 is preferably provided with end lugs 2 which may be formed integrally therewith or secured thereto. 60 Firmly secured by any suitable means, such as riveting, welding or the like, to the face of the base plate 1 is a series of mold forming plates, including a leg 3 overlying the base plate and a leg 4 normal thereto and 65 to the base plate. These right angle mold members, comprising legs 3 and 4, are arranged in longitudinal abutting series, and the last member of the series is preferably formed by the single plate 3' with no right 70 angularly disposed leg, as the function of the latter will be subserved by the end plate which crosses the open ends of all the individual mold sections, as will be more particularly explained hereinafter. The inner 75 face of each of the mold members 3 and 3' is provided with a projection 5, which may take any desired form, and which constitutes the core for forming the frog in the block or brick.

80 In order to build up a multiple mold, the series of the units, such as illustrated in Fig. 4, are assembled in parallel relation with the angular legs 4 normal to each base plate engaging the rear face of the adjacent 85 base plate, as illustrated in Fig. 1, and, when the units have been assembled in requisite number, end plates 6 are applied, by passing the tongues 2 on the respective ends of unit base plates 1 through slots 8 in the said 90 end plates. The end plates are also provided with vertical angle bars 7, which determine the width of the multiple mold section, the base plate of the initial unit being supported and aligned by the angle irons 7 on the 95 end plates. The final base plate of the series, represented by the reference character 1', may, if desired, be a plain section of the same dimensions as the other base plates, which is engaged behind the angle irons 7. 100 In other words, the final base plate 1' may have the mold forming sections, formed by the right angle plates 3 and 4, omitted therefrom, but in other respects is substantially 105 identical with the other base plates 1.

When a multiple mold is to be assembled on a smooth floor or molding bed, the base plates 1 and the right angle plates attached thereto are of the same height, but, if a smooth floor like surface is not available, it 110 is desirable and necessary to provide the multiple mold with an underlying support

which will present a smooth surface for the bottom of the multiple molds, and the supporting element is preferably made in the form shown in Fig. 2, involving a relatively wide face plate 15, which is of substantially the same length as base plate 1 of the individual mold units, and which is supported by angle irons 16, the whole constituting a bench like element, and when several of these are arranged side by side, they will constitute a smooth, level support for the entire series of mold sections. When the apparatus is used in conjunction with the supporting elements, certain of the base plates 1 are made of a greater depth than the attached mold plates 3 and 4, so that the lower edges of the deeper base plates shall overhang the edges of the supporting plates 15, thereby not only insuring the proper adjustment and alignment of the various base plates, but materially strengthening the assembled mold as a whole. The supporting elements 15 may, if desired, be made wide enough to receive several of the mold forming sections carried by the individual base plates 1, in which event only those base plates which lie adjacent the lateral edges of the supporting members 15 would be extended downwardly to a greater depth than the mold forming plates carried thereby. Such a disposition and arrangement of the supporting member 15 is illustrated in Fig. 1, in which the multiple mold is supported on a truck, the latter having the usual framework, including transverse beams 20 and supporting wheels 21, said cross beams being provided with cleats or abutments 23 properly spaced to receive the end plates 6 as well as intermediate spacing blocks 24 interposed between the cleats and the base plates or mold sections to prevent the latter being sprung out of shape. Any suitable means may be provided for positively locking the individual base plates or mold forming units to the end plates, so that the assembled multiple mold may retain its proper shape, and, when such an assembled multiple mold or longitudinal series of multiple mold frames are applied to a supporting truck, as illustrated in Fig. 1, the latter is provided with upwardly extending yoke or stake members 22, between which and the end plates 6 of the mold section or sections wedges or other clamping means may be applied.

As indicated, the multiple mold may be extended longitudinally by placing two or more of the frames, with the assembled mold forming elements therein, in longitudinal alignment, the end plate 6 of one of the mold frames serving as a division plate between the two sections, the slots 8 therein preferably being made large enough to receive the lugs on the ends of the base plates of each section.

From the foregoing description it will be apparent that the apparatus involves material elements of economy in construction and application, in that, in its simplicity of form for use on smooth and level floors, it includes only two types of individual elements, namely, the mold forming members, each comprising a base plate 1 and mold forming members 3 and 4 attached thereto and the end plates 6, and even when the apparatus is employed with the separate supporting members 15, the number of unit types are increased by two only, the supporting members 15 and the mold forming members, including the deeper base plates 1. The apparatus is also much simpler and more efficient in operation than similar devices, as heretofore developed, in that it may be readily assembled by unskilled laborers, and, after the pour has been made, and the bricks or blocks allowed to set, the entire apparatus can be quickly taken down to release the bricks or blocks without danger of damaging or chipping the latter; as the mold forming sections may be readily withdrawn laterally from the rows of molded bricks or blocks as soon as the end plates have been displaced. Furthermore, the simplicity of the construction insures the apparatus and the elements thereof against damage or impairment during ordinary usage, and, should any one of the units be damaged, it may be readily replaced by another, as all of the units of the same type are interchangeable.

What I claim is:

1. A multiple mold for concrete bricks and the like comprising end plates, a series of interposed longitudinal mold forming members each including a vertical base plate and a series of right angle plates secured in contiguous alignment on said base plate, and means for securing the end plates and the mold forming members together.

2. A multiple mold for concrete bricks and the like comprising end plates having slots therein, a series of interposed longitudinal mold forming members each including a vertical base plate and a series of right angle plates secured in contiguous alignment on said base plate, and tongues on the ends of the mold forming members engaging the slots in the end plates.

3. A multiple mold for concrete bricks and the like comprising end plates, a series of interposed contiguous longitudinal mold forming members each including a vertical base plate and a series of right angle plates secured to said base plate with one leg of each right angle plate overlying the base plate and the other leg normal thereto, and means for securing the mold forming members to the end plates.

4. A multiple mold for concrete bricks and the like comprising a parallel series of unit mold forming members each including a ver-

tical base plate and a series of right angle plates secured in longitudinal alignment on said base plate with one leg parallel with the base plate and the other normal thereto, and 5 end plates secured to the respective ends of the series of mold forming members.

5. A unit section for multiple molds comprising a plain base plate adapted to be sup-

ported on one longitudinal edge and a series of right angle plates secured in contiguous 10 alignment on said base plate one leg of each right angle plate overlying the base plate and the other leg normal thereto.

In testimony whereof I affix my signature.

FRANK J. KINZINGER.
